BALL POINT PEN

Tobias T. Kaplan, 156 Sharpe St., Cleveland, Miss.

Filed May 6, 1960, Ser. No. 60,474

Term of patent 14 years

(Cl. D74—17)

Fig. 1 is a side elevational of a ball point pen showing my new design;

Fig. 2 is an other side elevational view thereof as it appears turned at an angle of 90°;

Fig. 3 is an enlarged end elevational view thereof looking in the direction of 3—3 of Fig. 1; and

Fig. 4 is an enlarged sectional view taken on the line 4—4 of Fig. 1.

I claim:

The ornamental design for a ball point pen, substantially as shown.
